(57) **CLAIM**

The ornamental design for a phone case, as shown and described.

DESCRIPTION

FIG. 1 is a front perspective view of a phone case showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a second back view, showing another state of the phone case thereof;

FIG. 10 is a partial enlarged view of the selected portion 10 in FIG. 1; and,

FIG. 11 is a partial enlarged view of the selected-portion 11 in FIG. 2.

The dash-dash broken lines shown in the drawings depict portions of the phone case that form no part of the claimed design. The dot-dash broken line circles and curved lines in FIGS. 1, 2, 10, and 11 are included for the purpose of illustrating the partial enlarged views and form no part of the claimed design.

1 Claim, 11 Drawing Sheets
